(57) **CLAIM**

The ornamental design for a bracelet, as shown and described.

DESCRIPTION

FIG. 1 is a perspective view of a bracelet showing my new design;

FIG. 2 is a top plan view thereof;

FIG. 3 is a bottom plan view thereof;

FIG. 4 is a side elevational view thereof;

FIG. 5 is a side elevational view thereof from the side opposite that shown in FIG. 4;

FIG. 6 is an edge elevational view thereof;

FIG. 7 is an edge elevational view thereof from the side opposite that shown in FIG. 6; and,

FIGS. 8-14 are views similar to FIGS. 1-7, respectively, but with the parts in a different position.
